UNITED STATES PATENT OFFICE

ALEXANDER BELDIMANO, OF BERLIN-CHARLOTTENBURG, GERMANY

PRESSURE ACCUMULATOR FOR GASES AND LIQUIDS

Application filed January 16, 1931, Serial No. 509,209, and in Germany October 22, 1930.

My invention relates to pressure accumulators for gases or liquids.

The pressure accumulators of the type described in the patent application Serial No. 5 371,948, Patent No. 1,817,226, August 4, 1931, have proved satisfactory under normal conditions; that means pressure accumulators which consist of an external pressure-resisting container and an internal container which need be gas- or liquid-tight only, and which transmits the pressure to the external container through the intermediary of a viscous tightening substance. Now, frequently special requirements have to be met, however, by these accumulators as to the height of the pressure and to the gases or liquids to be stored up therein, which requirements cannot be completely complied with by this construction. My invention has therefore for its object to so improve pressure accumulators of the above type that all conditions can be met. This object is attained primarily by a plurality of nested internal containers being provided, made from metal, concrete or the like, the intermediate spaces existing between the largest thereof and the outer pressure-resisting container being filled with a viscous tightening substance which acts as pressure-transmitting means. According to the agents to be stored and to the height of the pressure to be taken up, the tightening substances inserted between the individual containers may possess different viscosity. It is further possible to dispense with the proper internal containers and to cover the inner surface of the external container successively with several layers of the tightening substance, the external film of each layer after application being prepared in such a manner by a suitable treatment, such as application of a painting or in any other manner, that the layer forms, so to speak, an internal container which acts exactly in the same manner as a normal container made from metal, concrete or the like. Under suitable geological conditions the strengthening of the external container can be replaced by rock pressure.

In order that my invention may be more readily understood, several embodiments of

the same are illustrated by way of example in the accompanying drawing, in which

Figure 1 is a horizontal section through a pressure accumulator forming the first embodiment of my invention.

Figure 2 is a similar section of another embodiment.

Figure 3 shows the third embodiment, while

Figure 4 illustrates the arrangement of my new pressure container in a rocky country.

As to be seen from Figure 1, the pressure accumulator is composed for example of several spacedly nested internal containers b^1 , b^2 which are disposed within an external pressure-resisting container a . The latter may be strengthened for example by tie bolts e situated in three planes and secured by nuts g . The spaces existing between the containers b^1 , b^2 , and a are filled with viscous tightening material denoted by c^1 and c^2 , which materials may possess different viscosity, to meet all requirements.

I further propose to have the internal containers b^1 , b^2 themselves entirely, dispensed with, by applying to the inner surface of the outer container a , first a layer c^1 of viscous tightening material and so preparing the surface thereof by a proper painting, a metal coating or in any other suitable manner, that so to speak a container b^1 is produced to which viscous tightening material c^2 is then applied, the surface of which is likewise to be treated in the described manner, whereby the internal container b^2 is formed. In this way a great number of layers can be formed which together afford a very satisfactory tightening effect, the pressure being again taken up by the external container a .

As to be seen from Figure 2, the containers may be strengthened also by tie rods f the ends of which carry wood thread h and which are likewise situated in three planes. Finally, as illustrated in Figure 3, the front walls of the external container a may be strengthened to one another by longitudinal rods e with nuts g , while the shell wall, if the container has cylindrical shape, is so re-inforced by metal rings or wire coils n that it is capa-

ble to resist to the radially acting pressure.

In rocky countries the strengthening of the external container or the container itself may be dispensed with, as illustrated in Figure 4.

5 Here the rock *a* itself forms, so to speak, the external container in which one or more inner containers *b*¹, *b*² are embedded, with suitable

10 tightening substances *c*¹, *c*² between them. It is particularly in this embodiment of my improved pressure accumulator that the above described method can be employed with particular advantage, because it may be difficult to build in the internal containers.

15 Therefore, after the proper cavity has been made in the rock, the walls thereof are coated with a viscous material the surface of which is then prepared by a suitable painting, metal coating or the like, whereupon the next tightening layer is applied thereto.

20 This operation may be repeated until the desired internal structure is attained which then again comprises several containers with intermediate tightening layers.

25 As is readily understood, the design of the inner structure depends upon the prevailing geographical and geological conditions; modifications of different kind may therefore be provided if required without deviating from the scope of my invention.

30 30 What I claim as my invention is:—

1. A pressure accumulator for gases or liquids consisting of a plurality of spacedly nested internal containers and an external pressure-resisting container, the spaces between these internal containers and between the largest thereof and the external container being filled with viscous pressure-transmitting tightening material of different viscosity.

40 40 2. A pressure accumulator for gases or liquids consisting of a plurality of spacedly nested internal containers and an external pressure-resisting container, the spaces between these internal containers and between the largest thereof and the external container being filled with viscous pressure-transmitting tightening material, the whole assembly adapted to be embedded in rocky ground whereby the rock structure takes up the pressure exerted upon the external container.

45 45 3. A pressure accumulator for gases or liquids consisting of a plurality of spacedly nested internal containers and an external pressure-resisting container, the spaces between these internal containers and between the largest thereof and the external container being filled with viscous pressure-transmitting tightening material, said inner containers consisting of hardened coatings

50 50 60 formed on the successive surfaces of the layers of tightening material to maintain said layers in place.

65 65 4. A pressure accumulator for gases comprising an external pressure resisting container and a plurality of spacedly nested in-

ternal containers, layers of viscous pressure-transmitting tightening material intermediate said containers, said internal containers being formed of hardened metallic coatings applied to the successive layers of viscous 70 tightening material.

The foregoing specification signed at Berlin, Germany, this 5th day of January, 1931.

ALEXANDER BELDIMANO.
